HEATER

Thomas C. Cheasley, Kansas City, Mo.

Application June 21, 1941, Serial No. 399,112

2 Claims. (Cl. 126—73)

This invention relates to heaters, particularly those of the type having magazines for containing and feeding solid fuels into a coking and burning zone, and has for its principal object to provide a heater of this character wherein combustion supporting air is supplied from the bottom to the top of the magazine thereby assuring an adequate supply of air for substantially complete combustion of the gases evolved in the upper part of the magazine.

Other objects of the invention are to assure an adequate supply of combustion supporting air across the top of the magazine to promote burning of the smoke and gases arising through the fuel; to provide the top of the magazine with a baffle for retarding discharge to the flue outlet; to provide a magazine formed of a plurality of juxtaposed refractories of substantially like size and dimensions and having the edges thereof interlocked with edges of the adjacent refractories; to provide the refractories with spacing means to maintain the air passages and provide adequate support of the refractories by the heater casing; to provide for control of air flow through the passages; and to provide the heater casing with an inner protective lining forming the outer side of the air passages.

In accomplishing these and other objects of the invention, as hereinafter described, I have provided improved structure, the preferred form of which is illustrated in the accompanying drawings, wherein:

Fig. 1 is a perspective view of a heater embodying the features of the present invention, a portion of the casing walls being broken away to better illustrate the interior construction.

Fig. 2 is a vertical section through one side of the heater.

Fig. 3 is a detail perspective view of the air control shutter.

Fig. 4 is a vertical section through the heater taken at right angles relatively to the section shown in Fig. 2.

Fig. 5 is a detail perspective view of a pair of the refractory blocks forming the fuel magazine.

Fig. 6 is a perspective view of the baffle forming the top of the fuel magazine.

Fig. 7 is a horizontal section through the heater on the line 7—7 of Fig. 4.

Referring more in detail to the drawings:

1 designates a heater constructed in accordance with the present invention, and which includes a base 2 supported from the floor by legs 3. Carried upon and secured to the base 2 is a casing 4, preferably formed of sheet metal and

having front and rear walls 5—6 and side walls 7—8. Supported on the upper edges of the walls of the casing is a top 9 having a front opening 10 closed by a door 11, through which the magazine is charged with fuel as later described. The top 9 also has an outlet opening 12 at the back thereof which is adapted to be connected with a pipe 13 leading to a chimney (not shown). Spaced above the top of the base 2 is a grate assembly 15 forming the bottom of a fuel magazine 16, later described, and the top of an ash-pit 17.

The grate assembly 15, illustrated in the present drawings, constitutes a circular plate 18 having openings 19 therein through which air passes from the ash-pit 17 upwardly through the fuel in the magazine. A central portion of the plate has an opening 20 through which ashes are discharged into the ash-pit for removal through a door opening 21 in the front of the heater, which opening is closed by a door 22 having a draft control damper 23. Supported below the opening 20 of the plate 18, on slides 24 and 25, is a shaker plate 26, having elongated openings 27 for discharging the ashes from the magazine. The shaker plate is adapted for reciprocation across the bottom of the grate with the aid of a poker or the like (not shown), which is engaged in an apertured ear 28 on the end of an arm 29 extending from the shaker plate to a point adjacent the ash-pit door opening 21, as shown in Fig. 4.

The grate plate 18 is carried by an outer plate 30 shaped to conform with the sides of the casing and to cooperate with the grate plate in supporting the fuel in the magazine. The outer plate 30 has openings therethrough to pass primary air in addition to that supplied through the openings 19. The marginal edges of the plate 30 form supporting ledge portions for the magazine and have spaced openings 31 therethrough for admission of air around the sides of the magazine when a control shutter 32 is opened.

The magazine 16 comprises a plurality of juxtaposed refractory blocks 33, arranged in superimposed courses to form the front and rear walls 34 and 35 and the side walls 36 and 37 of the magazine, the walls being spaced from corresponding walls of the casing to provide air passages 38 which are connected at their lower ends with the openings 31. The refractories 33 are best illustrated in Fig. 5, and are shown as comprising a substantially rectangular block 39 having a thickness to support the weight of the fuel. The side edges of the blocks have ship-lap joints

40 whereby the refractories interlock with adjacent refractories and prevent passage of radiant heat through the joints. The upper and lower refractories in the courses also have ship-lap joints 41 whereby the courses are retained in vertical alignment. The refractories have openings 42 therethrough, which may be of any desired shape but preferably incline upwardly to connect with the passages 38 so that the gases evolved incidental to coking of the fuel are readily directed into the passages for combustion therein.

10 Since the evolved gases are ignited in the passages, it is desirable to provide the walls of the casing with a suitable liner 43 to protect them from the intense heat of the flames, which liner may be a heavier sheet metal, cast metal plates, cast refractories, or a refractory plastic coating applied directly against the inner faces of the casing walls to form the outer sides of the passages.

In order to stabilize the refractories and assure spacing thereof from the walls of the casing, the rear faces are provided with lugs 44 which bear against the lining material. A sufficient number of courses are used so that the magazine extends approximately to the lower edge of the door opening, but the courses are spaced from the top of the heater to leave a combustion chamber 45 in communication with the outlet 12. In order to prevent direct flow of gases to the outlet 12, the top of the magazine carries a baffle or deflector 46, having an inclined top 47 resting on the rear liner and sloping upwardly toward the door opening 10 to terminate substantially in alignment with the upper edge thereof. The sides of the baffle are provided with wings 48 and 49 having support on the upper edges of the liner 43.

To guide the fuel into the magazine, and prevent spilling thereof over the top of the baffle, the forward edge thereof is provided with a rearwardly inclined flange 50. The flange 50, while being of a sufficient height to guide the fuel into the magazine, is low enough for flow of gases on their way to the outlet.

The shutter 32 is best shown in Fig. 3 and includes side bars 51 and 52, having spaced openings 53 therein arranged to register with the openings 31 in the outer ledge-like portion of the grate assembly, the openings 53 being spaced apart so that the spaces 54 therebetween form closures for the openings 31 in one position of the shutter. The side bars of the shutter are connected at the ends by bars 55 and 56, which are adapted to move in closing relation with the openings 31 at the front and back of the heater at the time the spaces 54 are registered with the openings 31 at the sides of the heater. The shutter is suitably mounted on guides or slides 57 carried at the sides of the heater, and the bar 55 is adapted to project through a slot 58 at the front of the heater. To facilitate manipulation of the shutter, the front bar 55 has a forwardly projecting tongue 59 carrying a knob or handle 60.

When starting a fire in a heater constructed and assembled as described, a fire is kindled on the grate assembly 15 and a sufficient amount of coal is inserted in the magazine to assure a good bed of live coals. The magazine is then completely filled with coal so that the fire burns from the bottom and converts the coal at the top into coke. The gases evolved during the coking process are discharged outwardly through the openings 42 in the sides of the magazine where they form combustible mixtures with the air moving through the passages 38 and wherein the gas is

burned with the flames playing against the walls of the heater casing. In order to assure the correct amount of air for the gases evolved, the shutter 32 is shifted so that the desired amount of draft air is passed from the ash-pit, the outer air being diverted directly through the grate into the magazine for supplying combustion supporting air for the coke, the proper amount of draft air being controlled by the draft door damper 23. With this arrangement, a sufficient amount of air passes to the upper portion of the heater for forming combustible mixtures with all of the evolved gases and any smoke which may arise through the magazine. The baffle 46 deflects the gases away from the outlet 12 so that they have sufficient time to complete combustion before being discharged to the chimney. As the coal cokes, it settles downwardly in the magazine and is burned in the bottom thereof to coke the additional coal emptied into the magazine. It is thus obvious that the heater, upon being charged with fuel, will operate over a long period without recharging or attention, as the feed of the fuel is substantially automatic. Since an adequate supply of air is admitted to promote substantially complete combustion, the heater operates without producing objectionable smoke or soot.

From the foregoing it is obvious that I have provided a heater of the magazine type which is of efficient operation and which is capable of burning bituminous or less expensive fuels.

What I claim and desire to secure by Letters Patent is:

1. A heater including a casing having side walls, a top and a bottom, a grate extending transversely within the casing and spaced above said bottom, a flue outlet connection in the upper portion of the casing, a refractory liner covering inner faces of the side walls above said grate, a fuel magazine above said grate and terminating short of the flue connection, refractories forming the walls of the magazine and spaced from the refractory liner to provide a gas burning space therebetween said gas burning space having connection with the space below said grate through air passages located adjacent the side walls of the casing, means for admitting air into the casing from below the grate to supply combustion supporting air through the grate for maintaining burning of the fuel in the lower portion of the magazine and to supply air through said passages for maintaining burning of gases in said gas burning space, said walls of the magazine having spaced openings along the height thereof to pass gases evolved from fuel contained in the magazine into the gas burning space, means for controlling admission of the air to the casing, separate control means for regulating flow of air through said air passages to the gas burning space, and a deflector bridging a portion of the top of the magazine including the gas burning space below said flue connection and having sides supported on said refractory liner to leave the gas burning space open under said deflector whereby burning gas issued from said spaces pass under the deflector and are deflected away from direct passage to the flue connection.

2. A heater including a casing having side walls, a top and a bottom, a grate extending transversely within the casing and spaced above said bottom, a flue outlet connection in the upper portion of the casing, a refractory liner covering inner faces of the side walls above said grate, a fuel magazine above said grate and terminating short of the flue connection, refractories form-

ing the walls of the magazine and spaced from the refractory liner to provide a gas burning space therebetween, said gas burning space having connection with the space below said grate through air passages located adjacent the side walls of the casing, means for admitting air into the casing from below the grate to supply combustion supporting air through the grate for maintaining burning of the fuel in the lower portion of the magazine and to supply air through said passages for maintaining burning of gases in said gas burning space, said walls of the magazine having spaced openings along the height thereof to pass gases evolved from fuel contained

in the magazine into the gas burning space, means for controlling an admission of the air to the casing, separate control means for regulating the flow of air through said air passages to the gas burning space, and a deflector bridging a portion of the magazine including the gas burning space below said flue connection and having support on said refractory liner, said deflector sloping upwardly over the top of the magazine and spaced from the refractories to leave the upper end of said gas burning space open thereunder and having an upwardly extending flange along the terminal edge thereof.

THOMAS C. CHEASLEY.
